UNITED STATES PATENT OFFICE.

ERICK J. SWEDLUND, OF WILLISTON, NORTH DAKOTA.

SEPARABLE CUFF BUTTON.

1,404,247.

Specification of Letters Patent. Patented Jan. 24, 1922.

Application filed December 30, 1920. Serial No. 434,004.

To all whom it may concern:

Be it known that I, ERICK J. SWEDLUND, a citizen of the United States, residing at Williston, in the county of Williams and 5 State of North Dakota, have invented certain new and useful Improvements in Separable Cuff Buttons, of which the following is a specification:

This invention relates to certain new and 10 useful improvements in cuff-buttons of the general class known as separable buttons designed more especially for soft shirts, and it has for its objects among others to provide a simple and cheap, yet positive and reliable 15 snap fastening embodying simple means for locking the members together and yet permitting ready separation when desired.

It has for a further object to provide a 20 button of this general character which shall be composed of few parts, those capable of manufacture at small cost, readily assembled and reliable and most efficient in use.

Other objects and advantages of the invention will hereinafter appear and the 25 novel features thereof will be particularly pointed out in the appended claims.

The invention is clearly illustrated in the accompanying drawing, which, with the numerals of reference marked thereon, forms 30 a part of this specification, and in which—

Figure 1 is an elevation with the female member in substantially central section with parts in locked position.

Figure 2 is a substantially similar view 35 showing the parts in position to be separated.

Figure 3 is a plan view of the locking or clutch members separated from the associated parts.

40 Like numerals of reference indicate like parts throughout the different views.

In carrying out my invention, I form the male member with the face portion 1, the rear portion 2, the intermediate neck or 45 shank portion 3, the rear portion 2 terminating in a substantially spherical or ball portion 4 having the small neck portion 5, the latter being in axial alinement with the intermediate portion or shank 3. This may 50 be made of any suitable material, in one or more parts as may be found most expedient.

The female member comprises the face portion 6, the shank 7 and the member 8, the free edges of which are bent inward to 55 ward each other forming the annular flange 9, the outer edge of which is bent inward,

as at 10, leaving the enlarged opening 11. It will thus be seen that the chamber or space 12 confined by the flange 9 is dovetail in shape or inwardly tapered, as seen 60 clearly in Figures 1 and 2.

Within this chamber or space are confined two discs 13 and 14. The disc 14 is provided with lugs or the like 15 which embrace the edge of the disc 13, as seen best in Figure 3, 65 it being noted that the construction is such that the discs may have sliding movement relative to each other. The disc 13 is provided with an axial opening 16, while the disc 14 is provided with an axial opening 70 17; these openings, however, are so disposed that one will be normally eccentric to the other, as seen in Figures 1 and 3.

The disc 14 has its outer face curved or raised, as seen at 18, being inclined toward 75 its opening, this being for a double purpose, namely to guide the ball 4 to the central opening making the coupling or uniting of the parts easy, and also providing convenient means to be reached by the thumb or 80 finger in separating the two parts of the button.

As seen in Figures 1 and 2, a small spring 19, preferably of wire, is placed between the two discs to normally hold the discs 85 in such position that the central opening in the disc 13 will be closed by the disc 14. This is when the discs are in the position shown in Figure 1, but when the discs are pressed inward, as in Figure 2, they will 90 have room to expand and adjust themselves so that the male member can be easily withdrawn, as will be evident from said Figure 2. The inward movement of the discs may be readily accomplished by pressure upon 95 the raised portion 18 of the disc 14. When the discs are pushed inward, by applying force to the ball 4, to separate the members 13 and 14, to separate or join the two parts of the button, the disc 13 slides to one side, 100 and when this is done the central openings will be concentric, but when the outside diameters of the discs are even the eccentric hole in the disc 13 will partially close the opening and the button will be locked after 105 the manner of a clutch.

The spring 19 finds an abutment against the lug or flange 20 on the disc 13.

Modifications in details may be resorted to without departing from the spirit of the 110 invention or sacrificing any of its advantages.

What I claim as new is:—

1. A separable button comprising a male member and a female member and a locking means comprising a head and relatively 5 movable members movable both inwardly and radially within a recess in said female member and having openings for the reception of said head normally eccentrically disposed, said members being guided one by 10 the other.
2. A separable cuff button comprising a male member and a female member and a connection embodying a ball and relatively movable discs movable both inwardly and 15 radially within a recess in said female member and having openings therein for the reception of said ball, said openings being normally eccentrically arranged with relation to each other.
3. A separable cuff button comprising a male member and a female member and a connection embodying a ball and relatively movable discs having openings therein for the 20 reception of said ball, said openings being normally eccentric with relation to each 25

other, and a spring interposed between said discs.

4. A separable cuff button comprising a male member and a female member and a connection embodying a ball and relatively 30 movable discs both movable inwardly and radially having openings therein for the reception of said ball, said openings being normally eccentric with relation to each other, the female member being provided with 35 a dove-tailed receptacle within which said discs are disposed.

5. A separable cuff button comprising a male member and a female member and a connection embodying a ball and relatively 40 movable discs having openings therein for the reception of said ball, said openings being normally eccentric with relation to each other, the female member being provided with a dove-tailed receptacle within 45 which said discs are disposed, and a spring interposed between said discs.

In testimony whereof I affix my signature.

ERICK J. SWEDLUND.
